UNITED STATES PATENT OFFICE.

JOHN HAYDUK, OF BROOKLYN, NEW YORK.

COLLAPSIBLE FIELD-CHAIR.

1,113,340.

Specification of Letters Patent.

Patented Oct. 13, 1914.

Application filed October 22, 1913. Serial No. 796,674.

To all whom it may concern:

Be it known that I, JOHN HAYDUK, a subject of the King of Hungary, residing at Brooklyn, in the county of Queens and State of New York, have invented new and useful Improvements in Collapsible Field-Chairs, of which the following is a specification.

My invention relates to portable chairs of the folding or collapsible type. It provides 10 a chair of this character which is of simple and durable construction, cheap to manufacture, and is so constructed that it folds up into such a small and conveniently shaped bundle that it can be carried around by a 15 person without the slightest discomfort.

Referring to the drawings in which I have illustrated the preferred form of my invention:—Figure 1 is a side view of the collapsible or folding chair constructed according 20 to my invention. Fig. 2 is a top plan view of the same with the flexible seat cover broken away for the purpose of showing the details of the joint. Fig. 3 is a side elevational view of the chair in the folded position. Fig. 4 is a bottom plan view of the disk member in which the legs and seat stays are journaled. Fig. 5 is a detail view of a 25 portion of a seat stay with the fastening element attached thereto.

Throughout the separate views the same 30 part is designated by the same reference character.

Referring to the drawings annexed hereto and forming a part of this specification; the 35 disk 1 carries four seat stays 2 suitably journaled therein at right angles to each other, the said seat stays 2 being pivoted to the channel plate 3 mounted on the underside of the disk 1 by means of the rivets 4. Pivotedly mounted at 5 on one side of each seat stay is an arm 6 having a flat abutting surface 7 lying in toward the disk 1 and, at its other end, it carries a lug or pin 8. Mounted 40 on the seat stays 2 is a split member 9 adapted to slidably move between the two pins 10—10 carried by the stays, and also adapted to slide over the ends 11 of the member 6 when said member is drawn down into position.

The outer ends of the seat stays 2 are turned upward and carry the T-shaped members 12 pivotally mounted thereto. The flexible seat covering 13 is riveted or otherwise suitably secured to the cross bars 5 of the T-shaped members 12, as is shown at 14. Pivotaly journaled in the disk 1 be-

tween each pair of seat stays is a leg member 15 each member having the eye portion 16 adapted to pivotally hold the said legs in place on the pins 17 carried by the disk 1. 60 The lower end of each leg carries an enlarged foot portion 18. At a suitable point midway of each leg is pivoted a supporting arm 19 carrying at its free end the bayonet slot 20 adapted to engage the lug 21, also 65 mounted on each leg.

The supporting arms, when in position, form a rectangle and join each leg to the next succeeding leg, thereby forming a substantial support for the legs and preventing 70 them from spreading when a load is carried by the chair.

The parts of the chair, when folded, assume the position shown in Fig. 3 and in order to set it up in the operative position, the chair is turned with the feet 18 upward and the legs are then pivotally swung downward. The supports 19 are hooked over their respective button lugs and the legs are then in position to support a load. To 80 bring the seat portion into the operative position, the arms 2 are brought downward until the flexible covering lies flat, then the members 6 are pulled down by means of catching hold of the lugs 8 until the ends 85 7 thereof hook under the surface of the disk 1. The split members 9 are then slid over the ends 11 of the members 6 and serve to retain the same in their downward position, as shown in Fig. 1, and also retain the seat 90 arms 2 in position. The chair is then ready to receive a load.

It is understood that various modifications of my invention may be made without departing from the spirit thereof.

Having thus described my invention, what I claim is:—

1. A collapsible field chair comprising in combination, a flexible seat portion, a disk member, seat supporting arms pivotally secured to said disk member, T-shaped members pivoted to said seat supporting arms and adapted to be attached to said flexible seat portion, locking arms pivotally mounted on said seat supporting arms and adapted at one end to engage the upper surface of said disk, a slidable member mounted on each of said seat supporting arms and adapted to engage said locking arms whereby said supporting arms are retained in extended, 110 position, legs journaled at one end in said disk member, a foot portion integral with

each of said legs, an arm pivoted to each of said legs and adapted to detachably engage the adjacent leg whereby said legs are supported.

- 5 2. A collapsible field chair comprising in combination, a flexible seat portion, a disk member, folding seat supporting arms pivotally secured to said disk member, means pivoted to said seat supporting arms adapted for attaching the said flexible seat portion thereto, means pivotally connected to said seat supporting arms and adapted to engage said disk member and retain said supporting arms in the extended position, 10 legs journaled in said disk member, and means carried by said legs whereby each leg may be detachably connected to the succeeding leg thereby forming a support for the said legs.
- 15 3. A collapsible field chair comprising in combination, a flexible seat portion, a disk member, folding seat supporting arms pivotally secured to said disk member, T-shaped members pivoted to the seat supporting 20 arms and adapted for attachment to said flexible seat portion, lever means pivotally connected to said seat supporting arms having one arm adapted to engage said disk and a fastening member carried by said seat 25 supporting arms whereby the other ends of said levers may be retained in such a position as to hold said lever in contact with

said disk, thereby retaining said seat supporting arms in the extended position, legs journaled in said disk member, and means carried by said legs whereby each leg member may be detachably connected with the succeeding leg member thereby forming a support for said legs.

4. A collapsible field chair comprising in combination, a flexible seat portion, a disk member, folding seat supporting arms pivotally secured to said disk member, means pivoted to said seat supporting arms adapted for attachment to said flexible seat portion, means pivotally connected to said seat supporting arms and adapted to engage said disk member and retain said supporting arms in their extended position, legs journaled in said disk member, a foot portion integral with each of said legs, an arm pivoted to each of said legs and having a bayonet slot in the free end thereof, buttons carried by each of said legs and adapted to engage the bayonet slots of said arms whereby said legs are detachably connected to each other and thereby supported.

In testimony whereof I affix my signature in the presence of two witnesses.

JOHN HAYDUK.
